UNITED STATES PATENT OFFICE.

GEORGE F. ROOKE, OF PROVIDENCE, RHODE ISLAND, ASSIGNOR TO ROOKE AUTOMATIC REGISTER COMPANY, OF PROVIDENCE, RHODE ISLAND, A CORPORATION OF MAINE.

REGISTER.

Application filed January 28, 1926. Serial No. 84,411.

The present invention relates to registers for receiving and counting coins and other devices representing value, whether real or arbitrary. For example the form of the invention here shown is adapted to the street railway business to be used by fare collectors in collecting fares from passengers, and in that case the evidences of value may be coins of currency, or tickets or tokens having arbitrary value for the particular purposes of the business. The utility and scope of the invention, however, are not limited to the business or use above mentioned for illustration, but applicable to any situations and combinations where coins and tickets or the like are to be collected and accounting rendered of their collection. Accordingly, the scope of the invention and of the protection which I claim relates to a register for any purpose connected with the receipt and counting of such coins, etc.

My present invention has for its object first to provide, for the use of such registers means for grasping the circumference of the inserted coin and pulling it into the register; second to provide, in connection with such a register having a movable coin carriage and a latch for holding it in set position, a simplified mechanism for setting such latch; and third to make such latch setting mechanism effective either to prevent a second operation of the counter when a coin has become caught under the latch and has failed to pass through the machine, or to give warning to the collector that the coin has become so caught. In patents granted to myself and to George W. Turk, disclosure has been made of gripping means adapted to engage the opposite faces of the coin, but when such grippers are sufficiently dull and encounter a coin which is sufficiently smooth they are liable to slip off from the coin without pulling it through. The coin grasping means which forms the subject of the present invention is independent of the roughness or smoothness of the coin, and depends on the diameter and peripheral outline of the coin for the purpose of gripping.

The embodiment of the invention chosen for illustration herein is a portable register adapted for the use of street railway conductors in collecting fares, and in the following explanation of the invention I shall describe it with particular reference to that embodiment and use, but with the under-

standing that the scope of the invention and the protection which I claim are not so limited. In this specification the term "coin" is used with generic significance as including tickets and all other articles of real or arbitrary value designed to be collected and counted with the aid of registers embodying this invention.

In the drawings forming a part of this specification I have shown the above specified embodiment of the invention removed from the case in which it is enclosed for use. That is, the drawings show the essential parts of the machine, without the case, which is practically necessary to safeguard the machine from being tampered with, but is not an essential so far as the novel principles of the present invention are concerned.

Figure 1 of the drawings is a front elevation of said machine;

Fig. 2 is a side elevation of the machine as seen from the right of Fig. 1;

Fig. 3 is an elevation similar to Fig. 1 of the upper part of the machine with omission of the setting mechanism;

Fig. 4 is a similar view showing the position of the grippers immediately after insertion of a coin;

Fig. 5 is a similar view showing the position of the carriage and coin grippers after the carriage has pulled in the coin;

Fig. 6 is a fragmentary sectional view taken on line 6—6 of Fig. 3;

Fig. 7 is a similar section taken on line 7—7 of Fig. 3 shown on an enlarged scale;

Fig. 8 is a perspective view of a fragment of the frame and the latch setting means associated therewith;

Fig. 9 is a perspective view of the locking dog by which the movable carriage is locked in said position;

Fig. 10 is a perspective view of the latch by which said lock is released;

Fig. 11 is a rear elevation of the machine;

Fig. 12 is a plan view of the machine.

Fig. 13 is a cross section taken on line 13—13 of Fig. 3.

Fig. 14 is a perspective view of the movable coin gripping jaw with its associated cam lever.

Like reference characters designate the same parts wherever they occur in all the figures.

The machine comprises a frame, having a passageway through it for the coin, a carriage

105

100

95

110

mounted to slide on the frame, a register, and coin-grasping, carriage-setting, and register-operating mechanisms associate with the parts above named. The frame, as here represented, 5 is a box-like structure having parallel external faces and composed of front and back plates 1—2 and spacing bars 3—4, there being an open space 5 forming a coin chute, between said plates and bars. The carriage 6 is formed 10 of members suitably shaped and connected to embrace the frame and have a sliding bearing thereon. A plate 7 having its opposite edges bent over at 8 and 9 fits freely in the interior space of the frame, and is structurally a part 15 of the carriage, being connected thereto by rivets or equivalent means 10 passing through a slot 11 in the rear of the frame, and spaced apart from the upper rear member of the carriage by a spacing block 12. The plate so formed 20 carries coin grippers 13 and 14, and may be termed the gripper-supporting part of the carriage.

On the front side of the frame is secured a plate 15, suitably mounted and spaced apart 25 from the frame to leave room for the travel of the carriage, and such plate affords support for a combined gear and cam wheel 16, an intermediate gear 17, a rack plunger 18, and mechanisms by which movement of said 30 plunger is adapted to rotate the wheel 16 in one direction. The means for imparting movement from the plunger to the wheel 16 may be the same as shown in prior patents, and are therefore not described herein. A pitman 35 19 is connected with a crank pin 20 on the wheel 16, and with a stud 21 on the carriage, said stud forming a wrist pin, and the pitman being connected to it by a screw 22.

On the rear side of the main frame is secured 40 a plate 23 on which is rotatably mounted a drum or spring barrel 24, containing a spring similar to the main spring of a watch, and around said barrel is wrapped a tape 25 secured at one end to the barrel and connected at 45 the opposite end to a pin 26 projecting from the carriage.

A register or counter 27 is secured to the frame and is driven from the gear wheel 17. Said counter may be of any character suitable 50 to be operated in the manner indicated, and therefore to count the number of trips of the carriage or values depending thereon.

Movement inward of the plunger 18, which 55 may be effected, when the machine is held in the operator's hand, by drawing the base of his thumb and the ends of his fingers toward one another, rotates the wheel 16 and raises the carriage through the action of pitman 19; at the same time drawing out the tape 25 and 60 winding up the spring in the barrel 24. The carriage is locked in its raised position by a latch plate 28 which is pivoted on the stud 21 and has a stud or lug 29 adapted to seat on a latch abutment 30 which projects from the 65 rear of the frame. A spring 31 is wrapped

about the stud 21, and one end of the spring bears against a pin 32 on the latch plate, while its other end acts against a stop pin 33 on the carriage. The pin 32 passes into a slot 34 in the pitman 19. When the carriage is being 70 raised the upper end of the pitman swings to the right, with respect to Figure 1, and by pressing on the pin 32 swings the latch plate aside far enough to enable its stud 29 to slide along the inclined side face 30^a of the abutment 30, and when this stud has passed said abutment it is snapped by the spring over the top of the abutment, the pitman having been in the meantime swung backward (to the left) far enough by continued rotation of the 80 wheel 16 to permit such movement. But the locking plate stud is prevented from immediately passing off from the abutment at the other side, by a trigger lever 35 pivoted by means of a rod 36 seated in a hole 37 in a block 38, which block is fastened to the front plate of the frame and is part of the same piece with the abutment 30. The trigger lever has a stop arm preferably equipped with a roller 39, which lies in the path of a stop finger 40 on the 90 latch plate, and in a position to obstruct said stop finger when the stud 29 is directly over the abutment 30. The trigger lever also has a trigger arm or finger 41 which extends across the upper end of the coin chute or space 5 in 95 the frame and is adapted to be displaced, so as to release the latch, when a coin is inserted.

In order to place the trigger in position for obstructing the latch plate when the carriage is being set, I provide a bell crank lever having arms 42 and 43, the same being preferably of a resilient character and made of a spring wire which is coiled about a stud 44 (about which it may turn as on a pivot) projecting from the block 38, the ends of said 105 wire being disposed to form the arms as shown. There is provided on the pitman 19 a cam surface 45 arranged to engage the offset end of arm 42, when rising and to move said arm to the left by cam action. The arm 43 lies close to the obstructing arm of the trigger and above a pin or abutment 46 on the latter, in such relation that, when the arm 42 is thus moved to the left, the arm 43 is moved downward and, by engagement with 110 the abutment 46, places or holds the obstructing arm 39 in the path of the latch stop finger 40. But when the pitman has passed to the limit of its movement in setting the carriage, a deep notch adjacent to the cam surface lies beside the engaging part of the arm 42, leaving the trigger controlling lever free to be moved by the trigger when the latter is 115 displaced by an inserted coin. Even without this freedom, however, the trigger can still be 120 depressed by the coin when the trigger controlling lever is of the springy construction here described.

The coin grippers 13 and 14 previously mentioned are arranged in the widest dimen- 125

sion of the coin passage, so that when the coin or ticket is inserted the grippers and the coin are in the same plane. These grippers extend above the frame and trigger to such distance that the widest part of the coin must pass within their extremities when the coin trips the latch. The grippers are nearest together at their extremities, and the space between them is widened below such extremities. One of the grippers, as the gripper 14, is movable, being pivoted to the carriage at a suitable point 47 below its extremity, and to it is connected an arm 48 lying close to the wall of the coin passage and thin enough to leave free space for the coin. This arm is offset so as to pass through a slot 49 in the front plate 1 of the frame, and through an opening 50 in the carriage, and its extremity lies in front of the carriage, having on its end a hook 51 connected by a spring 52 with a pin 53 on the carriage. The part of the arm 48 which passes through the slot 49 lies near an arm 54 on the latch plate and under a pin 55 which projects rearwardly from said arm. A cam 56 is formed on that part of the arm 48 lying nearest the pin 55.

When the machine is set in position to receive the coin, the latch plate is engaged with the latch abutment 30 and with the trigger, and is in the position shown in Figure 3. Then the pin 55 lies at one side of the cam 56. When the coin is inserted and trips the trigger, the latch plate immediately swings to the left, with respect to Figure 3, and the pin 55 rides up on the cam surface 56, thereby tilting the gripper finger 14 toward the fixed gripper 13, at the same time that the latch stud 29 passes clear of the abutment 30. The carriage is then free to be moved, and is suddenly moved downward, pulling the coin with it. It will be understood that the movement given to the coin gripper by the cam is sufficient to bring the extremity of the finger 14 nearer to the extremity of finger 13 than the width of the coin, and as the coin must be inserted between the fingers far enough to carry its greatest width beyond the extremities of the fingers before it releases the latch, the coin cannot be held back by the passenger but is positively engaged and pulled into the machine. Although I have applied the name "grippers" to the members which thus engage the coin, they are grippers only in the sense that they prevent the coin from being withdrawn or held back. They do not or need not otherwise restrain the coin, but preferably are so formed as to leave a clear space through which the coin may drop to the lower end of the passage in the frame, and thence into the collector's hand; or into any other depository provided in connection with the machine.

The movement of the locking plate in the direction thus described is limited by a tail piece 58 on the plate 28 which comes into en-

gagement with the pin 33, the latter being thus a stop for the latch plate as well as an abutment for the latch plate spring. When the latch plate is thus arrested, its lug or stud 29 is clear of the latching abutment 30 and its pin 55 is over the top part of the cam surface 56; and such portion of the cam surface is so nearly at right angles to the path in which the cam has its movement about the finger 14, that the pin 55 acts as a positive lock which cannot be displaced by any force applied to the gripper 14, and thus prevents the coin from being released from the grippers.

Coin grasping means of the character thus described are evidently effective no matter what may be the condition of the surfaces of the coin, whether rough or smooth, and are therefore effective in circumstances where pointed fingers adapted to engage the faces of the coin would slip off and be ineffective. These present fingers are effective with all circular coins or token of the appropriate diameter, or with tokens of other shape provided they have different widths in different parts, with a portion of narrower width related to a portion of greater width and to the advancing extremity of the token in a substantially equivalent way to that herein described.

As the carriage is moved under the influence of the spring it imparts movement to the wheel 16 through the pitman 19, and thence to the counter 27. The value of the gear train between the wheel 16 and the counter is such that the complete rotation of the wheel 16, caused by the movement of the carriage and subsequent resetting of the carriage, causes registration of the value which is prescribed as that of the coin or ticket for which the machine is adapted.

I have previously stated that latching of the carriage in the set position is effected by the latch stud 29 passing across the top of the latch abutment 30, and being arrested in that position by the trigger arm 39. If the trigger arm should not be in position to arrest the latch plate, the carriage would not remain in set position, but would immediately make another trip and register another indication on the counter, without insertion of another coin. It may happen in some rare instance by an unusual combination of circumstances that a coin would be caught back of the trigger finger 21 and fail to pass through the passage, thus holding the trigger out of the way of the latch plate and permitting another registration to be made without insertion of another coin, as last described. In order to prevent or retard the setting movement of the carriage in these circumstances I provide in the cam surface 45 of the pitman a notch 59 so located that the end of the lever arm 42 enters it during the upward movement of the pitman. That side

of the notch which then comes to bear against the end of the lever is very slightly inclined to the lever arm and to the direction in which it moves when thus engaging said arm; its 5 inclination being sufficient to act with a cam action in moving the lever when there is no obstruction in the way of the trigger, but not to move the lever if the latter is of rigid construction, or to move it against a greatly 10 increased resistance if it is of springy and yielding construction, when the trigger is obstructed by a coin. The impedance thus given to the lever by the movement of the pitman either prevents the carriage being advanced far enough to become latched, or opposes so much resistance to the final setting movement, that the collector is warned in time to cease application of pressure to the 15 said plunger and remove the obstructing coin, before bringing the carriage into the fully set and latched position.

The foregoing description, and particularly those parts thereof which define the relations of various parts to one another, and 20 their movements, with reference to the horizontal and vertical, have been given with reference to the drawings, for convenience and clarity, and without limiting intent. The protection which I claim applies to the mechanism and essentially equivalent constructions without regard to the position which they may happen to occupy. My protection 25 also includes equivalent members and structures in other machines than those adapted to be held in the collector's hand.

It is to be understood that ordinarily when the machine is provided for use, it is enclosed in a case which has an entrance slot for the coin at the upper end and an outlet at the 30 lower end, the entrance slot being between the gripping fingers near their extremities, and so positioned that the passenger may push the coin far enough in to trip the latch. But as the present invention involves no 35 change from prior constructions in regard to the casing, I have omitted illustration of the casing herein.

What I claim and desire to secure by Letters Patent is:

- 50 1. A register comprising a frame having a coin passage, a pair of grippers movably supported with respect to said frame and arranged at the opposite sides of the wider dimension of and within the entrance to said passage, whereby to receive the perimeter of a coin inserted between them, and means for setting said grippers to a distance apart at their extremities less than the widest part of such coin.
- 60 2. A register comprising a frame having a passage adapted to receive a relatively wide and thin article the width of which differs at different distances back from its advancing end, a pair of grippers movably mounted with respect to said frame having engaging

portions adapted to travel from a position near the entrance to said passage and within the same into another position within said passage, said engaging portions being separated from one another, when in the first 70 position, by a distance wide enough to receive a wider part of such article, and means for shifting one of said grippers to narrow the distance between said engaging portions.

3. A register comprising a frame having a coin passage, a carriage movably mounted with respect to said frame, grippers mounted on said carriage at opposite sides of the wider dimension of said passage and having coin engaging portions nearer to one another than other parts of said grippers, means tending normally to hold the engaging parts of said grippers at a relatively wide distance apart, a lock for holding said carriage in a position where said grippers are near the entrance 80 to said passage, a spring tending constantly to withdraw said carriage to a position where the grippers are within the passage, a latch operable by a coin inserted between said grippers for releasing said lock, and means operable upon release of said latch for so moving one of the grippers as to diminish the width of the space between their nearest 85 points.

4. In a register, a frame having a coin passage, a carriage mounted on said frame, coin grippers mounted on said carriage and movable in said passage adjacent to opposite sides of the wider dimension thereof, a lock for holding said carriage with the grippers in such position adjacent to the entrance of said passage that a coin entering the passage will pass between the grippers, means for moving said carriage so as to withdraw the grippers into the passage, one of the grippers being movable toward and away from the other, means for placing said movable gripper at a relatively wide distance from the other gripper when the carriage is in the locked position set forth, a coin operated trip for releasing said lock, and means operated by said lock when released for moving the movable gripper toward the other gripper.

5. In a register, a frame having a coin passage, a carriage, grippers mounted on said carriage and located in said passage at opposite sides thereof, one of said grippers being movable relatively to the carriage and having a cam portion, a lock plate connected to the carriage and having a cam rider to cooperate with said cam, and a spring acting on said plate tending to move it so that its cam rider will travel over said cam.

6. In a register a carriage, complementary grippers mounted on said carriage, one of which is movable so as to move toward and away from the other, a spring engaged with said movable gripper tending to move it away from the other, a cam associated with said movable gripper, and a cam rider mount-

ed on said carriage and spring actuated to travel over said cam so as to shift the movable gripper toward the other gripper.

7. In a register, a frame having a coin passage, a carriage mounted movably on said frame, grippers carried by said carriage and movable therewith along said passage, one of the grippers being movable also toward and away from the other, an arm extending from said movable gripper and having a cam element, a spring acting on said arm tending to separate the movable gripper from the opposite gripper, a lock plate on said carriage cooperating with the frame to lock the carriage in a given position, a spring acting on said lock plate tending to move it out of locking position, and a cam rider on said lock plate cooperating with said cam element to displace the movable gripper toward the other gripper when the lock plate is so moved.

8. A register comprising a frame having a coin passage, a carriage movably mounted on said frame, coin grippers mounted on the carriage in said passage and arranged to embrace the perimeter of an inserted coin, a trigger mounted on the frame and extending across the passage adapted to be displaced by an inserted coin, a lock carried by the car-

riage for cooperating with the frame to hold the carriage in a position where said grippers are near the entrance to said passage, means tending constantly to withdraw the carriage from said position, means tending constantly to release said lock, a stop connected with said trigger for obstructing said lock when the trigger extends across the passage, one of the before named grippers being movable toward and away from the other to vary the width of the space between them and having an associated cam element, a spring acting on said gripper tending to move it away from the other gripper, a cam rider associated with said lock operating upon the cam to move the movable gripper toward the other gripper when the lock is released, a lever coacting with said stop and trigger for placing them in the positions above set forth when the carriage approaches its set position, means associated with the carriage for so actuating said lever, and means controlled by the lever for obstructing such movement of the carriage when the trigger is obstructed by a coin in the coin passage.

In testimony whereof I have affixed my signature.

GEORGE F. ROOKE.
